UNITED STATES PATENT OFFICE

FAIRFIELD W. HOBAN, OF NEW YORK, N. Y., ASSIGNOR TO FAIRFIELD SPECIALTIES CORPORATION, OF NEW YORK, N. Y., A CORPORATION OF NEW YORK

COIN TESTING APPARATUS

Application filed April 24, 1929. Serial No. 357,715.

My invention relates to improvements in means for and methods of testing coins, tokens, or like devices to determine whether the same are genuine or spurious, and the invention has for its object more particularly to provide a novel method for electrically detecting or indicating the presence of spurious coins, tokens or like devices and distinguishing therebetween and the genuine to enable rejection of such spurious devices, and, in performing said method, to provide a simple, efficient, and reliable apparatus which operates automatically to accept the genuine pieces or devices and to reject the spurious or counterfeit ones.

Another object of the invention is to provide an apparatus of the character specified which depends for operation in accepting a genuine coin or token upon a property or quality of such genuine coin or device not possessed by the various spurious or counterfeit devices presented thereto, the latter being rejected because of the absence of said specific or particular property or quality therein.

Another object of the invention is to provide an apparatus of the character specified which accepts or rejects metallic coins or tokens depending on the value of the electrical or ohmic resistance thereof.

Another object of the invention is to provide an apparatus of the character specified in which the means for controlling the acceptance of the coin or token becomes responsive only upon development of a current of predetermined value obtained when a genuine coin or token is presented for test and not obtained when other coins or tokens are presented.

Another object of the invention is to provide an apparatus of the character specified in which one means thereof discriminates in general between metallic and non-metallic coins, tokens, slugs or the like devices presented thereto, rejecting the non-metallic de-

vices, and another means thereof discriminates between the various metallic devices presented thereto, rejecting the devices having a composition differing from that of genuine coins or tokens.

Another object of the invention is to provide an apparatus of the character specified which directly returns the spurious or counterfeit coins, slugs or like devices to the person presenting the same, and which diverts the genuine coins or tokens either to a coin box or to a point for operating other mechanism.

Another object of the invention is to provide an apparatus of the character specified in which an impedance is employed for economically reducing the amount of current utilized when the apparatus is idle, and eliminating the use of switches or cut-outs likely to cause surges of current upon the closing of the circuit resulting in faulty operation, and in which means becoming effective in the presence of the coin, token or like device is employed for reducing the impedance to permit of the flow of current of a strength substantially inversely proportional to the resistances of the devices presented.

Other objects will in part be obvious and in part be pointed out hereinafter.

To the attainment of the aforesaid objects and ends, my invention consists of the novel features of construction, and in the combination, connection and arrangement of parts and in the steps constituting said method hereinafter more fully described and then so pointed out in the claims.

In the accompanying drawings:

Figure 1 is a front elevation showing one form of apparatus constructed according to and embodying my invention;

Fig. 2 is a sectional view thereof on the line 2-2 of Fig. 1, looking in the direction of the arrows;

Fig. 3 is an elevation at one side thereof;

Fig. 4 is a plan thereof;

Fig. 5 is an elevation at the opposite side thereof;

Fig. 6 is a detail sectional view on the line 6—6 of Fig. 5, looking in the direction of the arrows; and

Fig. 7 is a circuit diagram.

Referring to the drawings the apparatus is shown as mounted upon a frame or support 10 having a front panel 12 and a rear panel 14, and preferably formed as a casing in which certain of the parts are received.

Electromagnets or solenoids 16, 18 and 20 are secured one above the other to the inner side of the panel 12, the same being provided with the reciprocating magnetic cores or plungers 22, 24 and 26 projecting at the forward ends thereof through the panel 12.

An electrical element 28 resembling a transformer, and constituting the means for testing the coins, tokens or like devices is secured to the inner side of the panel 12 laterally of the solenoids. This element includes an endless magnetic core 30, preferably of laminated construction, and a multi-turn coil 32 thereon in circuit with a source of alternating current and constituting a choke or impedance. A U-shaped member 34 for controlling or reducing the impedance of the coil 32 is also mounted on the core 32 in insulated relation thereto, and the same normally forms an open circuit having a gap 36 therein. The ends of the member 34 extend through an opening 38 in panel 12 to be exposed at the front thereof for engagement with the coin or like device to form a closed endless circuit.

A vertically extending guideway 40 for the coins or tokens is disposed upon the front of the panel 12 over the opening 38, said guideway 40 having an entrance opening 42 at the upper end through which the coin or token is inserted and an opening or outlet 44 at the lower end through which the coin or token, if spurious or counterfeit, is returned to the person inserting the same. A cup 46 for receiving the returned coin or token is secured to the panel 12 below the guideway 40.

Suitable means 48 for diverting the genuine coins or tokens from the guideway 40 are disposed below the transformer 28 upon the panel 12. This means includes a chute member 50 pivoted at 52 within an opening 54 in panel 12 communicating with the guideway 40, the pivot 52 being so located that the open upper end 56 of member 50 normally tends to swing by gravity out of the guideway 40 to permit of the free passage of the spurious or counterfeit pieces to the return cup 46. The lower laterally extending portion of the member 50 is provided with a discharge opening 58 from which the coins are directly discharged into a suitable receptacle 59 therefor, or first into operative relation to other devices, such as bells or other signalling or indicating devices, or other mecha-

nism to be controlled by said coins, with which mechanisms the selector apparatus embodying the present invention may be incorporated.

The member 50 is preferably formed as a magnetic armature controlled, as herein-after described, by the electromagnet or solenoid 60 mounted on a bracket 62 secured to the inside of the panel 12. A spring detent 64 engages the member 50 when the latter is moved by the energized solenoid 60 and retains the member 50 in position with the end 56 thereof extending into the guideway 40 after the magnet 60 becomes deenergized, the member 50 being released from the detent 64 by impact of the coin with the latter as the coin passes through the opening 58. The circuit of electromagnet 60 is controlled in turn by the electromagnet 66 of a special relay type having an armature 68 pivoted at 70 below the same, and normally hanging by gravity in disengaged relation to the solenoid 66. The armature 68 has a predetermined weight of a value such as to be attracted only when the current through the relay has a predetermined value. When the armature 68 is lifted the electrical contacts 72 thereon engage the contacts 74 to close the circuit of solenoid 60. The solenoid 66 is in circuit with the primary coil 32 of the transformer or 28 as hereinafter described.

The opening or slot 42 through which the coin or token is inserted is of substantially the size necessary to receive a coin or token of the desired denomination or diameter, while excluding coins or tokens of greater diameter. Coins or tokens smaller than those for which the opening 42 is designed pass through the guideway 40 without operating the mechanism and are returned into the receptacle 46.

At opposite sides of the slot or opening 42 are spring electrical contacts 76 and 78 in the circuit of the solenoid 16. These contacts are spaced apart sufficient to permit of the passing therebetween of metallic coins or tokens A of the desired diameter which latter engage the contacts 76, 78 to complete the circuit of solenoid 16 to energize the same. Genuine coins or tokens and spurious metallic pieces of less diameter pass the contacts without closing the circuit of magnet 16, and likewise non-metallic pieces or slugs.

The outer ends of the movable plungers or cores 22 and 24 of the magnets 16 and 18 are pivotally connected to the arms 80 and 82 of the member 84 journaled in suitable bearings 86 on the front of panel 12. The member 84 has a vertically extending forked arm 88 having a recessed support 90 at the end thereof. The support 90 carries an electrical contact 92, cooperating with a contact 94 upon a pivoted member 96, the contacts being normally pressed toward each other by spring 98.

The support 90 also carries a combined 5 detent and coin retaining member 100 pivoted intermediate its length at 102 and having the inner end thereof 104 adapted to project through an opening 106 in the guideway 40 into the path of the coin immediately below the transformer 30, and having the outer end 108 normally pressed downwardly by a spring 110 into engagement with the 10 inner face of the pivoted member 96 to maintain the contacts in disengaged position. The support 90 is guided by a member 112 secured to the panel 12 and carries a freely 15 slideable pin 114 which, when the detent 100 is moved outwardly together with the support 90, engages the guiding member 112 and forces the lower end of the member 96 inwardly to permit of the detent 100 engaging the same under the action of spring 110. 20 The contacts 92 and 94 control the circuit of the electromagnet 20 which is actuated to press a spring arm 116 having an insulating button 117 thereon against the coin or token A in engagement with the ends of the 25 secondary 34, and bridging the gap 36 therein. For this purpose when the coin or other metallic piece A engages the detent 100 the latter is depressed releasing the member 96 and closing the circuit of magnet 20. When 30 the plunger 26 moves inwardly the same actuates a cam 118 fixed to a shaft 120 rotating in bearings 122 on the panel 12, the shaft 120 being actuated through an arm 124 having an opening 126 receiving the member 26. The 35 inward movement of the arm 124 is cushioned by means of a spring 128 coiled about the plunger 26 between the nut 130 at the end of shaft 126 and a sliding washer 132 thereon engaging the outside of the arm 124. 40 This arrangement permits of continued movement of the plunger 26 after the cam 118 has fully depressed the spring member 116.

The movement of the plunger 26 also controls the closing of the contacts 134 and 136 45 in the circuit for the electromagnet 18 for effecting the retraction of the detent 100 which retraction causes the opening of the contacts 92 and 94 to deenergize the circuit of magnet 20 to release the arm 116 and permit the coin or token A to travel to its destination.

In order to allow for a maximum building up of the current through the secondary 34 when the metallic piece A is in position therein, the movement of the contacts 134, 136 towards closing position is retarded by suitable means, such as the dashpot 138. The retarding device or dashpot shown comprises a cylinder 140 secured to the panel 14 and receiving a tubular piston 142 which carries the contact 134. Secured within the piston is a nut 144 serving as an abutment and having an opening in which the inner end of the plunger 26 is slidably received, the latter being retained therein against withdrawal by a

pin 146. A coil spring 148 is disposed about the plunger 26 between the abutment 150 secured thereon and the abutment 144. When the electromagnet 20 is deenergized the resiliency of the system controlled thereby returns the parts to inoperative position, the outward movement of the arm 124 being limited by hook 152. The member 84 is also frictionally retained in each position thereof by the spring 154.

At Fig. 7 is a wiring diagram showing the connections for the several contacts, impedance coil and electromagnetic devices above described, the current being preferably taken from the usual power line carrying alternating current.

The apparatus depends primarily for operation on characteristics, properties or qualities of genuine or good coins or tokens, such as the silver, copper and nickel alloy coins of the United States and may be employed for testing and assorting coins of the various denominations. The characteristics of the coin which is relied on is its ohmic resistance. The silver coin, for instance, has a resistance which is lower than that of any other metal from which slugs or spurious coins are usually made, such as from iron, aluminum, lead and the like, and the apparatus herein shown and described as one embodiment of the invention is arranged for operation with silver coins.

In operation, when the apparatus is not in use and the member 34 is open, the high impedance of the coil 32 and core 30 effectively retards or reduces the flow of alternating current from the main line for the purpose of obtaining economy in the use of current.

When coins or tokens which are smaller than the opening 42 are inserted the coin slides immediately through the guideway 40 into the return box 46 without actuating the mechanism. Obviously coins too large to pass through the guideway cannot be used. When the coin or other device of the proper size is inserted, the device engages the contacts 76 and 78. If such coin or device is of non-metallic or non-conducting material, the same slides through the guideway 40 into the return box 46 without actuating the mechanism.

My apparatus therefore initially rejects coins or devices which are not of the required size or denomination or which are of non-conducting material, thereby preventing by a simple expedient the use of a large class of slugs or other spurious pieces made of substances such as glass fibre or the like.

If the device inserted is a metallic one of the proper size, the same engages the contacts 76 and 78 closing the circuit of the electromagnet 16 and causing the stop 100 to move into the guideway 40 to prevent the coin or other device A from passing to the return box 46. As the coin or device A strikes the

detent or stop 100, the latter releases the member 96 closing the circuit of the magnet 20 and causing the arm 116 to press the device A firmly against the ends of the member 34 closing the circuit thereof and thereby reducing the impedance effect of the coil 32 and allowing a current to flow, which varies in substantially inverse proportion to the resistances of the various devices.

With the apparatus shown, when a silver coin of known resistance closes the secondary gap 36 the increase in current strength or amperage will be sufficient to magnetically raise the armature 68, and cause the chute 50 to move into the guideway 40, devices or slugs of higher resistance being incapable of operating armature 68. Meanwhile the contacts 134 and 136 close causing the retraction of the member 100 and spring member 116 to release the coin, the latter passing into the return box 46 if spurious or counterfeit, or into the chute 50 if genuine or good.

A characteristic or feature of the present invention is the provision of means, such as the diverting means 48, responsive only to the predetermined current strength or amperage obtained when a genuine coin or token closes the gap 36, for indicating or making known the character of the token or coin, whether the same is genuine or spurious, and/or for controlling the disposition of the coin, token or like device according to the character thereof. The invention is applicable for testing coins, such as silver, which has a resistance lower than all slugs of other metals usually employed, or for testing coins, such as copper or nickel-copper alloys which have resistances of values intermediate the values of the resistances of the slugs of the various metals, some of which may have a lower resistance and some of which may have a higher resistance than the genuine coin or token.

Another characteristic or feature of my invention resides in the impedance means 28 which permits of the use of alternating current, and serves to effectively retard or reduce the flow of current when the apparatus is not in use. When the coin or token closes the gap 36 the coin is traversed by a relatively small current incapable of causing sparking or unduly heating the coin, and the resulting increase in current through the coil 32 is gradual and accurately corresponds to the coin resistance.

Were the circuit of the testing means controlled by cut-outs or circuit makers or breakers the closing thereof would cause momentary increases in current flow corresponding to that for a genuine coin or token even in the presence of a false coin, resulting in the inadvertant acceptance of such false coin or device by the diverting means 48.

In the present embodiment of my said invention the testing of the tokens or coins is

accomplished first, by testing the size or denomination thereof and discriminating between metallic and non-metallic devices, rejecting all devices except metallic ones of the proper size, and secondly, by testing such metallic devices, all metallic devices not having the particular property or quality of the genuine or good coin or token being rejected.

Further, the means for controlling the disposition of the metallic devices is responsive only to some single property possessed by good coins or devices and not possessed by the spurious coins or devices. Metallic coins or devices presented for test and not satisfying the condition imposed on the apparatus for operation are rejected, thereby rendering unnecessary a number of testing means each dependent for operation on a different property of the several kinds of slugs or spurious devices which may possibly be submitted for test.

Apparatus embodying my said invention may be incorporated with other apparatus, if so desired, such as telephone pay boxes, turn-stiles, vending machines, automatic money changes and the like.

I claim:

1. An apparatus of the character described comprising a guideway for a coin, token or like device having an opening for the insertion of the device and an outlet for returning the device to the person inserting the same, means associated with said guideway for testing various electrically conducting devices presented thereto, an electrically actuated member movable into said guideway to retain the device in operative relation to said testing means, said member being normally in inoperative position, a circuit therefor having contacts contiguous to the entrance to said guideway and controlled by the devices inserted, a circuit for said testing means, and a member movable into said guideway below said testing means and controlled by said last named circuit to divert the device from said guideway when the reaction thereof on the testing means is that of a genuine or good device.

2. An apparatus of the character described comprising a guideway having an entrance opening and a return outlet, means operated electrically by conductive coins, tokens or like devices inserted through said entrance opening to prevent passage of said devices to the return outlet, said means being unresponsive to non-conductive devices to permit of the return thereof, means for testing the composition of the conductive devices retained in said guideway by said electrically operated means, said testing means including a circuit subjected to the effects of the conductive devices and in the presence of a genuine or good device developing a current flow of predetermined amperage, means for causing the return of the electrically operated means to in-

operative position to release the conductive device tested, and means responsive to said current of predetermined amperage, to the exclusion of currents of other amperages produced by spurious devices, for diverting the genuine devices from the guideway.

3. An apparatus of the character described comprising a guideway for a coin, token or like device, testing means associated with said guideway, means movable into and out of the path of the device for retaining the device in operative relation to the testing means, and means actuated by contact of said device with said retaining means to press said device against said testing means.

4. An apparatus of the character described comprising a guideway having entrance and discharge openings, means associated with said guideway for testing coins, tokens or like devices, means operated electrically by the device and movable into said guideway to retain the device in operative relation to said testing means, and means operated electrically by said device for pressing the device against said testing means.

5. An apparatus of the character described comprising means for testing coins, tokens or like devices, a guideway thereto, a stop normally in inoperative position movable into said guideway for preventing passage of said device past said testing means, electromagnetic means controlled by said device for actuating said stop, means for pressing said device against said testing means, electromagnetic means controlled by the engagement of said device with said stop for actuating said pressing means, and means controlled by said last named electromagnetic means for releasing said device.

6. An apparatus of the character described comprising a guideway having a direct passage for the return of coins, tokens or like devices, a circuit associated with said guideway having means for engagement with the devices to vary the current in said circuit substantially in inverse proportion to the resistance of said devices, said circuit being immune to devices of non-conductive material, and means responsive to the current of the amperage obtained upon contact of a genuine coin or token with said engaging means for diverting the coin or token from said guideway.

7. An apparatus of the character described comprising a circuit having an impedance therein, means for controlling the effect of said impedance including a normally open secondary circuit adapted to be closed by a coin, token or like device, whereby to vary the current in the impedance circuit substantially in inverse proportion to the resistance of said devices, and means responsive to a current of predetermined amperage in said circuit for indicating whether the device is genuine or spurious.

8. An apparatus of the character described comprising a magnetic core, a circuit adapted to carry alternating current and having an impedance coil disposed about said core, a conductive member disposed about said core and having a gap therein, said conductive member forming a closed circuit with a coin, token or like device to decrease the effect of the impedance coil and cause current in said first named circuit substantially inversely proportional to the resistance of the devices closing the circuit of the conductive member, and means responsive only to a current of predetermined amperage for indicating the nature of the devices being tested.

9. An apparatus of the character described comprising a guideway for coins, tokens or like devices, stopping means movable into said guideway, a circuit including a member having a gap facing said guideway, said member when closed by a genuine device causing a current of predetermined amperage in said circuit, electrical means operated by the device inserted for moving said stopping means into said guideway to prevent the passage of the device below said gap, means for pressing said device against said gap, electrical means operated by engagement of the device with said stopping means for actuating said pressing means, said electrical means having a delayed movement, electrical means operated by said last-named electrical means for releasing the device, a chute movable into said guideway for diverting the device if genuine therefrom, and electrical means responsive only to said current of predetermined amperage for actuating said chute.

10. An apparatus of the character described comprising a guideway open at the upper and lower ends thereof and receiving coins, tokens or like devices, stopping means movable into said guideway and normally withdrawn therefrom, electromagnetic means having a circuit provided with contacts at the upper end of said guideway and controlled by the device inserted, if the device is conductive, for moving the stopping means into said guideway, a closed magnetic core, a circuit including an impedance coil disposed about said core and adapted to carry alternating current, a U-shaped member about said core constituting an open secondary circuit facing said guideway above said stopping means, said secondary circuit when closed by a genuine device causing a current of predetermined amperage in said first named circuit, electrical means operated by said device for pressing the device against said member, means operating automatically for releasing said pressing means and said stopping means and having a delayed action, a chute movable into said guideway for diverting the device, electromagnetic means for controlling said chute, and electrically operated means responsive only to said current of predetermined am-

- perage for controlling the circuit of said last-named electromagnetic means.
11. An apparatus of the character described comprising electrical means for testing coins, tokens or like devices, means actuated thereby for controlling the disposition of the device, stop means for retaining the device in operative relation to the testing means, and device controlled means for moving the stop means to and from operative position.
12. An apparatus of the character described comprising electrical means for testing coins, tokens or like devices, means actuated thereby for controlling the disposition of the device, stop means for retaining the device in operative relation to the testing means, said stop means including a circuit controlling member, electrical means energized by insertion of the device for moving said stop means to operative position, and electrical means controlled by engagement of the device with said circuit controlling member for returning the stop means to inoperative position.
13. An apparatus of the character described comprising means for testing the composition of coins, tokens or like devices including a circuit subject to the effects of conductive devices and in the presence of a good device developing a current of predetermined amperage, means responsive to said current of predetermined amperage, to the exclusion of currents of other amperages produced by spurious devices, for diverting the genuine devices, stop means for retaining the device in operative relation to the testing means, means operated by the device inserted for moving said stop means to operative position, and means for returning the stop means to inoperative position.
14. An apparatus of the character described comprising an impedance circuit normally restricting the flow of current therein, means adapted to be engaged by coins, tokens or like devices for reducing the impedance and developing a current flow in the circuit varying with the resistances of the devices, and means selectively responsive to the current developed in the presence of a genuine device for controlling the disposition of the devices.
15. An apparatus of the character described comprising an impedance circuit normally restricting the flow of current therein, means adapted to be engaged by coins, tokens or like devices for reducing the impedance and developing a current flow in said circuit varying with the resistances of the devices, means for pressing the device into engagement with said impedance reducing means, and means selectively responsive to the current developed in the presence of the genuine device for controlling the disposition of the devices.
16. An apparatus of the character de-
- scribed comprising a circuit having means for engaging coins, tokens or like devices to vary the current therein in accordance with the resistances of the devices, said circuit including electromagnetic means controlling the disposition of the devices and adjusted to be responsive to the devices of least resistance and immune to devices of greater resistance.
17. An apparatus of the character described comprising an impedance circuit normally restricting the flow of current therein, means adapted to be engaged by coins, tokens or like devices for reducing the impedance and developing a current flow in the circuit varying in inverse relation to the resistances of the devices, means for resiliently pressing the device into engagement with the impedance reducing means, means for controlling the engagement and disengagement of the pressing means and device, and means responsive to the current developed in the circuit in the presence of devices of least resistance and immune to devices of greater resistance for controlling the disposition of the devices.
18. An apparatus of the character described comprising an electrical circuit including a contact for testing coins, tokens or like devices, means responsive to current in said circuit for controlling the disposition of the device, stop means movable into the path of the device to retain the device in position relative to said contact, electrical means controlled by insertion of the device for moving said stop means to operative position, means for pressing the device against the contact, electrical means for actuating the pressing means and returning said stop means to inoperative position, and means for retarding the releasing movement of the stop and pressing means.
19. An apparatus of the character described comprising electrical means for testing coins, tokens or like devices, means actuated thereby for controlling the disposition of the devices, stop means moved by the device into operative position to retain the device in position relative to the testing means, means for pressing the device against the testing means, and common means for actuating said pressing means and said stop means to return the latter to inoperative position.
20. An apparatus of the character described comprising electrical means for testing various electrically conducting coins, tokens or like devices presented thereto, a movable chute associated with said testing means and controlled thereby for controlling the disposition of the device, a normally inoperative electrically actuated member for retaining the device in operative position relative to the testing means, and a circuit therefor having contacts adjacent to the entrance for the device to insure closing of the

circuit by insertion of the device across said contacts.

21. An apparatus of the character described comprising a closed magnetic core, a circuit including an impedance coil disposed about said core, a member on said core having a gap and constituting an open secondary circuit adapted to be closed by a coin, token or like device to vary the current in 10 said first named circuit, said secondary circuit when closed by a genuine device producing in said first named circuit a current of predetermined value, guiding means actuated in response to said circuit of predetermined 15 value for controlling the destination of the device, stop means actuated by the insertion of the device for retaining said device in position relative to the gap of said secondary member, means for pressing the 20 device against said secondary member, and means for controlling said pressing means and the movement of said stop means to inoperative position.

22. An apparatus of the character described comprising a circuit having an electromagnetic coil therein, means for presenting coins, tokens or like devices of various compositions to said circuit to cause current through said coil inversely proportional to 30 the resistances of the various devices, and means controlled by the magnetic effect of said coil for controlling the disposition of the device, said last named means being made responsive to the magnetic effect of the particular value developed upon presentation of the genuine device to the circuit without being responsive to the magnetic effects developed upon presentation of devices of other resistances to said circuit.

40 23. An apparatus of the character described comprising a circuit having an electromagnetic coil therein, means for presenting coins, tokens or like devices of various compositions to said circuit to cause current through said coil inversely proportional to the resistance of the various devices, and means controlled by the magnetic effect of said coil for controlling the disposition of the device, said last named means including 45 an armature adjusted to be responsive to the magnetic effect of the particular value developed upon presentation of the genuine device to the circuit and to be immune to magnetic effects developed upon presentation 50 of devices of greater resistances to said circuit.

24. An apparatus of the character described comprising an impedance circuit including electromagnetic means and adapted 55 to be traversed by a fluctuating current, means for presenting coins, tokens or like devices of various compositions to said circuit to reduce the impedance and cause current through said electromagnetic means inversely proportional to the resistances of the

various devices, and means controlled by the magnetic effect of said electromagnetic means for controlling the disposition of the device, said last named means being made responsive to the magnetic effect of the particular value developed upon presentation of the genuine device to the circuit without being responsive to the magnetic effects developed upon presentation of devices of other resistances to said circuit.

70 25. The herein-described method of distinguishing between genuine and spurious coins, tokens or like devices which consists in presenting the device to a circuit and utilizing the device to vary the current as a function of the electrical resistance of the device, and utilizing the magnetism developed by current of certain of the amperages obtained to the exclusion of the magnetism developed by current of other amperages for producing mechanical movement indicating the character of the device presented.

75 26. The herein-described method of distinguishing between genuine and spurious coins, tokens or like devices which consists in presenting the device to a circuit and utilizing the device to vary the current as an inverse function of the electrical resistance of the device, and translating the current of the amperage obtained in the presence of a given device to the exclusion of current of the amperages obtained in the presence of other devices into mechanical movement for indicating the character of the device presented.

80 27. The herein-described method of distinguishing between genuine and spurious coins, tokens or like devices which consists in presenting the devices to a circuit and utilizing the devices to vary the current in inverse relation to the electrical resistance of the devices, and translating the current of the amperage obtained in the presence of a genuine device of silver composition to the exclusion of current of other amperages obtained in the presence of spurious devices into sensible form for indicating the presence of the genuine device.

85 28. The herein-described method of distinguishing between genuine and spurious coins, tokens or like devices which consists in presenting the devices to a circuit and utilizing the devices to vary the current in inverse relation to the electrical resistance of the devices, and translating the magnetism developed by current of certain of the amperages obtained to the exclusion of the magnetism developed by current of other amperages into form for mechanically diverting certain of the devices relative to others thereof.

90 29. The herein-described method of distinguishing between genuine and spurious coins, tokens or like devices which consists in presenting the devices to a circuit and utilizing the devices to vary the current in inverse relation to the electrical resistance of the de-

vices, and translating current of the amperage obtained in the presence of a genuine device to the exclusion of current of the amperages obtained in the presence of other devices into a sensible form for indicating the presence of said genuine device.

5 30. The herein-described method of distinguishing between genuine and spurious coins, tokens or like devices which consists in presenting the device to a circuit and utilizing the device to vary the current as a function of the electrical resistance of the device, and mechanically controlling the disposition of the device by the magnetic effect of the current developed in the presence of the device of least resistance while preventing such mechanical control by magnetic effects of lesser intensity produced in the presence of other devices.

10 31. The herein-described method of distinguishing between genuine and spurious coins, tokens or like devices which consists in presenting the device to a circuit and utilizing the device to vary the current as an inverse function of the electrical resistance of the device, and translating said current, only when of the predetermined amperage obtained in the presence of a good device, into sensible form for indicating the character of the device presented.

15 32. The herein-described method of distinguishing between genuine and spurious coins, tokens or like devices which consists in presenting said device to an impedance circuit and utilizing the conductivity of the device for reducing the impedance and causing a flow of current which varies as a function of the resistance of the device presented for test, and translating the current of certain of the 20 amperages obtained into sensible form for making known whether the device tested is genuine or spurious.

In testimony whereof, I have signed my name hereto.

45 FAIRFIELD W. HOBAN.
